(57) **CLAIM**

The ornamental design for a shroud for an electronic device mounting bracket, as shown and described.

DESCRIPTION

FIG. 1 is a top, front, left side perspective view of a shroud for an electronic device mounting bracket showing our new design.

FIG. 2 is a bottom, front, left side perspective view thereof.

FIG. 3 is a front elevational view thereof.

FIG. 4 is rear elevational view thereof.

FIG. 5 is a top plan view thereof.

FIG. 6 is a bottom plan view thereof.

FIG. 7 is a left side elevational view thereof.

FIG. 8 is a right side elevational view thereof.

FIG. 9 is an elevational view of the shroud for an electronic device mounting bracket of FIG. 1 in an exemplary position of use atop a bus stop.

FIG. 10 is an elevational view of the shroud for an electronic device mounting bracket of FIG. 1 in an exemplary position of use adjacent to a streetlight pole; and,

FIG. 11 is an elevational view of two shrouds for electronic device mounting brackets in exemplary positions of use adjacent a streetlight pole.

The dot-dash broken lines in the drawings define the bounds of the claimed design while all other broken lines are directed to environment. None of the broken lines form any part of the claimed design.
